COP WINDING MACHINE

Wilhelm Reiners, Gustav Kahlisch, and Stefan
Fürst, Gladbach-Eheydt, Germany, assignors
to W. Schlaforst & Co., Gladbach-Eheydt,
Germany, a corporation of Germany

Application February 25, 1939, Serial No. 258,360
In Germany March 5, 1938

4 Claims. (CL 242—31)

In building up a package of yarn or thread to form a cop it is a common practice first to wind a layer or layers of filament of about one quarter the length of the cop, and then to wind successive layers with successive shifts away from the base, either the yarn guide or the spindle or cop tube being moved to produce the shift.

Our invention is concerned with cop winding machines in which the laying of the filament is effected with the aid of a traversing device, e. g. a grooved traverse drum, and according to the invention the shift referred to is produced by means of a feed mechanism comprising a feeler wheel which is engaged by the returning filament when for the time being maximum diameter is attained, and is thereby rotated. This feeler is intermittently moved out of contact with the package, and this movement is transmitted to the traverse drum or equivalent traverse device.

The drum and the feed mechanism are combined into a unit, herein called a builder unit, by means of a frame. The drum may have a single helical groove, giving controlled traverse in one direction only, with return traverse due only to the slant of the filament fed to the drum, one advantage of this construction being that it enables the winding to be performed at higher speed, and another being that with a one way groove a drum of smaller diameter can be used. The action of the feeler wheel is improved if the path of its progressive movement is inclined to the axis of the winding spindle.

The invention is illustrated in the accompanying drawings, in which

Figs. 1 and 2 represent one form of construction, Fig. 1 being a sectional elevation and Fig. 2 a section on the line II—II of Fig. 1.

Fig. 3 is a sectional elevation of another form of construction, and

Fig. 4 is a section on the line IV—IV of Fig. 3.

Figs. 5 and 6 are a side view and front view respectively, of a modified form of the builder unit, and

Figs. 7 and 8 are similar views illustrating another modification.

Referring first to Figs. 1 and 2, a friction wheel 1 on the main driving shaft engages a friction wheel 2 on the winding spindle 3. The yarn or thread F normally holds a detector 4 out of contact with a slidable rod 5, but on fracture of the yarn the detector tilts by gravity against the rod 5, causing the same to actuate a lever 6 whereby the friction wheel 2 is retracted from contact with the wheel 1, against the action of a spring 7.

The cop tube H is held between a collar 8 on

the spindle 3 and a cupped head 9 in a bearing facing the spindle. A gear wheel 10 on the spindle 3 engages a gear wheel 11 on a shaft 12 driving a helically grooved traverse drum 13. The shaft 12 is flattened on one side. The drum 13 has a single helical groove extending from near one end to near the other, with short oppositely directed extensions at its ends. There being only this one groove, controlled traverse of the yarn takes place only in one direction, the traverse in the opposite direction being due only to the slant at which the yarn is fed to the drum. The short, oppositely directed extensions of the groove afford brief guidance to the yarn when it becomes disengaged from the main groove at the end of the controlled traverse, and when it is about to enter the main groove at the end of the uncontrolled traverse, which is limited by the yarn meeting a guide or deflector 15.

A boss at one end of the drum is engaged with a slotted extension 17 of a bracket 16 projecting from a slide 18 mounted on a spindle 19 and a guide bar 20. The spindle 19 has a screw thread on one side, and is flattened on the other side. It has rotatably mounted on it a feeler wheel 23, the hub of which is internally threaded to engage the threads of spindle 19. The hub of the feeler can be pushed against the flat side of spindle 19, to disengage the threads of the hub from the threads of the spindle 19 and permit the feeler to be moved freely lengthwise of the spindle. The hub of feeler wheel 23 is held in engagement with the threads of spindle 19 by a spring 27, which bears against a short arm 28 pivoted at 29 and formed with a ring portion surrounding the hub of wheel 23. A finger 29 serves as a handle for throwing arm 28 to the right (Fig. 2), to disengage the feeler wheel from the threads of spindle 19, so that the bracket 16 can slide freely along the bar 20. The spindle 19 and bar 20 are connected with each other by bars 21, 22 to form a small frame. The bar 20 has revolubly mounted on it a collar 24, which can be fixed to it by means of a set screw 25. The collar has an arm resting against an abutment 26, whereby the collar is restrained from rotation. By angularly adjusting the bar 20 in the collar the normal distance of the wheel 23 from the cop tube can be regulated.

A worm 40 on the spindle 3 engages a worm wheel 41 on a shaft 42, to which is fixed a cam 43. The bar 20 is axially movable, and a boss 44 at its left hand end (Fig. 1) is held against the cam 43 by a spring 45, so that during rotation of the cam the bar is reciprocated, and reciprocates the bracket 16 and the drum 13.

The winding of a cop starts with the feeler wheel frame 18 and thread guide mechanism shifted to the left, in Fig. 1, as far as it will go. The cop tube H rotates clockwise (Fig. 2) and the thread F passes from thread guide 14, part way around traverse drum 13, to the cop tube. The thread is moved on the outward part of its traverse by the helical groove of drum 13 and on the inward part by the pull due to the slant of the thread. When the cop has built up to a certain diameter, the thread on the return of the traverse movement engages under feeler wheel 23 and rotates it a little, moving the frame 18 to the right by the amount of the thread diameter. Meanwhile the cam 43 causes an intermittent to-and-fro movement of the frame 18, parallel to the axis of the spindle, in which movement the feeler wheel and traverse drum take part. This supplementary movement withdraws the feeler wheel 23 from contact with the cop and modifies the action of the traverse drum, with the result that the feeling action is made more delicate and less liable to damage the thread, and the thread is laid more perfectly at the reversing point.

When the cop has attained the required length the thread guide 14 is rocked slightly to the left (Fig. 2), finger 29 is operated to release the feeler wheel from the threads of spindle 19, and the feeler and traverse unit is pushed back to starting position, winding back the thread over the top in a quick spiral. The cop is then released by pulling out button 9' and a new tube is inserted.

The construction shown in Figs. 3 and 4 is the same as that shown in Figs. 1 and 2, in all parts except the builder mechanism and thread traverse mechanism. In this case the screw spindle is not capable of rocking with respect to the cop spindle, the feeler wheel being mounted to rock about the screw spindle instead. A shaft 19a mounted to reciprocate in bearings 70 and 71, and a shaft 20a mounted to reciprocate in bearings 72 and 73 are united into a frame by cross bars 21 and 22. A yoke 18a is slidably mounted by bearings 67, 68, and 69 on shafts 19a and 20a and between its arms is a box 74, which supports the feeler wheel 23. The feeler wheel is carried by a shaft 75 rotatably mounted in a bearing 76 and carrying a spur gear 33 at its inner end. The gear 33 meshes with a gear 34 revolvably mounted on spindle 19a. The spindle is threaded on one side and flat on the other, like spindle 19, except that the threads are on the opposite side of the spindle. The hub of gear 34 is internally threaded, to engage the threads of spindle 19a. A rock shaft 77 mounted in a bearing 78 has fixed to it outside box 74 a finger 29a and on its inner end an arm 28a formed with a ring surrounding the hub of gear 34. A spring 27a presses arm 28a to the right (Fig. 4) and holds the hub of gear 34 in engagement with the threads of spindle 19a. Projecting rigidly from bearing 69 of yoke 18a is a slotted guide 79, through which passes a screw 25a threaded into a hole in the box 74.

Extending rigidly from bearing 69 of yoke 18a is a bracket 18z, which bears at its upper end a strap 30 surrounding a boss 31 on traverse drum 13a. The traverse drum, which, in this case has a single continuous groove, is fixed to a shaft 12a. The shaft 12a, which is rotatably and slidably mounted in bearings 82 and 83, is keyed by flattened sides in the hub 84 of a gear 11a. The shaft 12a can slide longitudinally in the hub 84 and a closed tube 35 may be provided to cover its projecting end.

In this case the cam 43 acts upon the end 44a

of spindle 19a, to impart a supplementary movement to the builder and traverse mechanisms. The device operates in substantially the same manner as the one first described. The adjustment of the feeler wheel 23 with respect to the cop tube is accomplished by loosening screw 25a, then rocking box 74 on spindle 19a.

In the modification shown in Figs. 5 and 6 the builder unit comprises a frame formed of a longitudinal bar 90, cross bars 91 and 92, and bearings 93, 94, 95 and 96. The bearings 93 and 94 are slidably mounted upon a round rack bar 19b, while the bearings 95 and 96 are slidably mounted upon a flattened shaft 12b. The rack bar 19b can be mounted in the same way as the spindle 19a of Fig. 3. The shaft 12b may be driven in the same way as the shaft 12 in Fig. 1. The bearing 96 has a tubular extension 97 on which is rotatably mounted a feeler wheel 23b. This feeler wheel has a hub 51 extending to the left, provided with a worm to engage a worm wheel 52 fixed to a shaft 97, which is rotatably mounted in a bracket 98 of cross bar 91. A gear 53 is mounted to slide longitudinally on shaft 97 and has an extended hub 99 keyed to the shaft 97 by a key 100. The hub 99 bears a milled button 54, against which bears a spring 101 pressed inward by a cap 102 on the end of shaft 97. Normally the gear 53 meshes with rack bar 19b and turning of the feeler wheel 23b moves the builder unit along the rack bar. For returning the builder unit to starting position the milled button 54 can be pulled out against the action of spring 101 to disengage gear 53 from rack bar 19b, permitting the builder unit to be slid along the rack bar.

Between the feeler wheel 23b and bearing 95 a traverse drum 13 is mounted on shaft 12b and keyed to it by the flat sides of the shaft. The feeler wheel 23b is cup-shaped and extends over the end of traverse drum 13 to the point where the helical groove of the traverse drum terminates in one direction. Thus the contact rim of the feeler wheel is positioned to coincide with the change in direction of the traverse.

Figs. 7 and 8 show a modification in which the detector or feeler 23c is mounted on a vertical shaft and is arranged so that the returning filament is caught in the angle between the surface of the cop cone and the side of the detector, thus ensuring that even with filaments of very high counts the wheel will be turned. The builder unit comprises a frame 18c provided with bearings 105 and 106 in which the trunnions 61 and 62 of a grooved traverse drum 13c are journalled. A shaft 12c flattened on two sides extends slidably through the drum 13c and is keyed to the drum by its flat sides. The trunnions 61 and 62 of drum 13c are slightly eccentric with respect to shaft 12c, so that the frame 18c is oscillated as the drum rotates. A fork bearing 107 of frame 18c embraces a rack bar 19c to guide the lower part of the frame in its oscillating movement. The feeler wheel 23c is fixed to a shaft 108 journalled in a bearing 109 on the horizontal arm 110 of frame 18c. The lower end of shaft 108 has fixed to it a pinion 50c meshing with rack bar 19c. As the feeler wheel 23c moves into contact with the package S, during its oscillation by the eccentric trunnions 61, 62, it is rotated and feeds the builder unit along the rack bar 19c. The intermittent contact of the feeler wheel 23 prevents constant friction with the top layer of the package, which might cause damage.

It will be understood that without departing from the principle of the invention the package

itself may be shifted, instead of shifting the traverse device and the detector or feeler.

What we claim as our invention and desire to secure by Letters Patent of the United States is:

1. In a cop winding machine, a winding spindle, a builder unit mounted for movement at least approximately parallel to the axis of said winding spindle and comprising a rotatable traverse member having helical guide means and a feed mechanism including a feeler adapted to feel the winding package and to actuate said feed mechanism to move said builder unit progressively along said winding spindle, and means for oscillating said feeler to withdraw the same intermittently from contact with the winding package.

2. In a cop winding machine, a winding spindle, a builder unit mounted for movement at least approximately parallel to the axis of said winding spindle and comprising a rotatable traverse member having helical guide means and a feed mechanism including a screw spindle at least approximately parallel to the axis of said winding spindle and a feeler wheel connected therewith adapted to feel the winding package and to coact with said screw spindle to move said builder unit progressively along said winding spindle, and means for oscillating said feeler to withdraw the same inter-

mittently from contact with the winding package.

3. A cop winding machine as described in claim 1, wherein said traverse member is in the form of a drum provided with a helical groove interrupted to cause the thread to run out of said groove near the limit of one part of its traverse, and means for guiding the thread to said drum at a slant with reference to the axis of said winding spindle, whereby the tension of the thread causes it to return to the limit of the other part of its traverse on escaping from said groove.

4. In a cop winding machine, a winding spindle, a builder unit mounted for movement at least approximately parallel to the axis of said winding spindle and comprising a rotatable traverse member having helical guide means and a feed mechanism including a feeler wheel mounted coaxially with said traverse member adapted to feel the winding package and to actuate said feed mechanism to move said builder unit progressively along said winding spindle, and means for oscillating said feeler to withdraw the same intermittently from contact with the winding package.
